UNITED STATES PATENT OFFICE

ARTHUR B. MODINE, OF RACINE, WISCONSIN, ASSIGNOR TO MODINE MANUFACTURING COMPANY, OF RACINE, WISCONSIN, A CORPORATION OF WISCONSIN

HEATING APPARATUS

Application filed September 25, 1925. Serial No. 58,543.

My invention relates to heating apparatus and particularly to heating apparatus which may be suspended from a ceiling or the like. The invention has among its objects the production of apparatus of the kind described which is extremely neat and attractive in appearance, convenient, compact, durable, efficient and satisfactory for use wherever found applicable.

10 In one embodiment of the invention, a hanger or bracket is screw-threaded to the end of a pipe which projects downward from a ceiling or the like, the pipe being part of a steam or hot water system. Carried by the hanger or bracket is a radiator which is preferably of the automobile type and communicates with a downwardly projecting pipe through a channel or passage formed in the hanger or bracket. An electric motor carried by the hanger or bracket drives a fan adapted to induce a circulation of air through the radiator. Carried by the motor shaft is a conical member adapted to distribute the heated air around 25 the room.

Many other objects and advantages of the construction herein shown and described will be obvious to those skilled in the art from the disclosure herein given.

30 To this end my invention consists in the novel construction, arrangement and combination of parts herein shown and described, and more particularly pointed out in the claims.

35 In the drawings, wherein like reference characters indicate like or corresponding parts:

Fig. 1 is a vertical section through apparatus embodying the novel features of my invention; and

40 Fig. 2 is a plan section taken on line 2—2 of Fig. 1.

In the drawing, the reference character 10 designates a pipe which forms part of a 45 steam or hot water system, the pipe 10 being arranged to suspend from a main 10' adjacent a ceiling or the like. Screw-threaded upon the pipe 10 is a hanger or bracket 11 which carries a radiator 12, the radiator 12 being preferably of the automobile type and

preferably comprising headers 13, which are connected by tubes 15 or the equivalent. Bolts 16 may be provided for securing the radiator 12 to the hanger or bracket 11. The bracket 11 preferably comprises divergent leg members 17 and 18, the leg member 17 having a passage 19 therethrough which operatively connects the radiator 12 with the pipe 10. The radiator 12 is preferably connected to a return pipe 20 through which 55 condensed fluid or hot water may be discharged. An electric motor 22 is secured to the leg members 17 and 18 by bolts 23, and is provided with a shaft 25 which projects through the radiator 12. Mounted upon the 60 lower end of the shaft 25 is a fan 27 which will induce the circulation of air through the radiator when it is driven by the motor 22. A converging apron 28 secured to the undersurface of the radiator 12 insures that 65 the fan 27 will operate efficiently. Secured to the lower end of the shaft 25 and positioned below the fan 27 is a conical member 30 adapted to spread or distribute the air 70 drawn through the radiator 12 by the motor 75 22.

Obviously, any number of units of the kind above described may be suspended from the ceiling of a room and when operated will circulate and heat the air in the 80 room. It will be noted that the motor 22 is not subjected to the heated air passing from the radiator 12 but is continually cooled by the cool air drawn into the radiator. The improved device is extremely simple, and 85 may be quickly and easily connected to the steam or hot water system.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. Heating apparatus comprising a pipe section adapted to be secured to a pipe for 100

supplying a heated fluid, said pipe section communicating with said pipe, a bracket secured to said pipe section and supported solely thereby, a radiator carried by said bracket, and communicating with said pipe section, and means carried by the bracket for inducing a flow of air through said radiator.

2. Heating apparatus comprising a pipe section adapted to be secured to a pipe for supplying a heated fluid, said pipe section communicating with said pipe, a bracket secured to said pipe section and supported solely thereby, a radiator carried by said bracket and communicating with said pipe section, a motor carried by said bracket, and a fan operated by the motor for inducing a flow of air through the radiator, said motor being mounted in a position wherein the air heated by the radiator does not strike it.

3. Heating apparatus comprising a pipe section adapted to be secured to a pipe for supplying a heated fluid, said pipe section communicating with said pipe, a radiator, means for inducing a flow of air through said radiator, and a one-piece bracket suspended from said pipe section and supporting said radiator and said means, said one-piece bracket having a passage therethrough communicating with said radiator and said pipe section.

4. In an apparatus of the class described, a heating unit, a bracket supporting said heating unit and having a passage for conducting heated fluid to said unit, tubular means for supplying a heated fluid to said passage and forming the sole support for said bracket, a motor supported by said bracket, a shaft driven by said motor and passing through said unit, and a fan mounted on said shaft on the side of said unit opposite to said motor for advancing air through said unit.

5. In an apparatus of the class described, a heating unit, a bracket comprising a pair of divergent arms supporting said heating unit, one of said arms being hollow and adapted at one end for communicating with fluid supply means and for communicating at its other end with said heating unit for supplying fluid thereto, a motor supported between said arms and means actuated by said motor for advancing air through said unit.

6. In an apparatus of the class described, a heating unit, a bracket comprising a pair of divergent arms supporting said heating unit, one of said arms being hollow and adapted at one end for communicating with fluid supply means, and communicating at its other end with said heating unit for supplying fluid thereto, a motor supported between said arms, a shaft arranged in a plane substantially perpendicular to that of said unit and driven by said motor, and a fan

mounted on said shaft adjacent one side of said unit for advancing air through said unit.

7. In an apparatus of the class described, a heating unit comprising spaced headers and tubular means connecting them, a bracket having one of its ends secured to one header and having its other end secured to the other header, said bracket having a tubular portion for conducting heating fluid to one of said headers, means carried by said bracket for advancing air through said heating unit, and tubular means for connecting said bracket to a fluid supply pipe and adapted to be the sole support of said bracket, said heating unit and said air advancing means.

8. In an apparatus of the class described, a heating unit, a bracket supporting said heating unit and having a passage for conducting heated fluid to said unit, tubular means for supplying a heated fluid to said passage and forming the sole support for said bracket, a motor supported by said bracket, a shaft driven by said motor and passing through said unit, a fan mounted on said shaft on the side of said unit opposite to said motor for advancing air through said unit, and means for deflecting the air after it has been advanced through said heating unit.

9. In an apparatus of the class described, a heating unit, a bracket comprising a pair of divergent arms supporting said heating unit, one of said arms being hollow and adapted at one end for communicating with fluid supply means and for communicating at its other end with said heating unit for supplying fluid thereto, a motor supported between said arms means actuated by said motor for advancing air through said unit, and means supported by said air advancing means for deflecting the air advanced thereby.

10. In an apparatus of the class described, a heating unit, a bracket comprising a pair of divergent arms supporting said heating unit, one of said arms being adapted at one end for communicating with fluid supply means, and communicating at its other end with said heating unit for supplying fluid thereto, a motor supported between said arms, a shaft driven by said motor, a fan mounted on said shaft for advancing air through said unit, and an air deflector mounted on said fan shaft.

11. In apparatus of the class described, a heating unit, a fan mounted adjacent one side of said heating unit, a motor having a shaft rotatably carrying said fan, and means mounted on said motor shaft adjacent said fan for distributing the air set in motion by said fan.

12. In apparatus of the class described, a heating unit, a fan mounted adjacent one

side of said heating unit, a motor having a shaft rotatably carrying said fan, and a conical member mounted on said motor shaft adjacent said fan for distributing the air set in motion by said fan.

5 In testimony whereof, I have hereunto signed my name.

ARTHUR B. MODINE.
